UNITED STATES PATENT OFFICE

163,511

AUTOMOTIVE VEHICLE

Ellwood O. Compton, Los Angeles, Calif., assignor
to Anthony Oberholtz, Los Angeles, Calif.

Application October 12, 1949, Serial No. 5,456

Term of patent 14 years

(Cl. D14—3)

To all whom it may concern:

Be it known that I, Ellwood O. Compton, a citizen of the United States, residing in Los Angeles, in the county of Los Angeles, and State of California, have invented a new, original, and ornamental Design for an Automotive Vehicle, of which the following is a specification, reference being had to the accompanying drawing, forming part thereof:

Fig. 1 is a top plan view of an automotive vehicle showing my new design.

Fig. 2 is a side elevational view thereof.

Fig. 3 is a rear elevational view.

Fig. 4 is a front elevational view.

Fig. 5 is a vertical sectional view of one side of the vehicle, the same being taken on line 5—5 of Fig. 2.

The opposite side of the vehicle is substantially similar to the side that is shown. The dominant features of the design reside in the portions shown in full lines.

I claim:

The ornamental design for an automotive vehicle, substantially as shown and described.

ELLWOOD O. COMPTON.
